DIRECTIONAL RADIO SYSTEMS

Jean Ortusi and André Robert, Paris, France, assignors to Compagnie Générale de Télégraphie Sans Fil, a corporation of France

Application November 22, 1952, Serial No. 322,102

Claims priority, application France November 27, 1951

9 Claims. (Cl. 343—107)

This invention relates to directional radio systems and more particularly to directional radio systems for use on very high frequencies.

Very high frequency directional radio transmitting and receiving systems are often required, for example in apparatus of the "radar" type, for obtaining the accurate bearing or direction of a target. They are also required for ascertaining the direction of an incoming ultra-high frequency wave and for other purposes.

In general, most known directional radio systems, whether transmitting or receiving, depend for their operation upon the directional qualities, i. e. the polar diagram of a transmitting or receiving aerial.

However, the polar diagram of an aerial, even an ultra short wave aerial, cannot be made as sharp and narrow as is desired except by making it of such dimensions as to be very inconvenient if not impracticable. In practice, it is difficult if not impossible to make the angle of the principal lobe of the polar diagram less than a few degrees, and consequently the directions taken with an aerial having such a diagram are prone to an angular error of at least a few degrees.

It has been proposed in directional radio systems to make use of two overlapping polar diagrams. By oscillating an ultra short wave aerial between directions defining a small angle between one another, and symmetrically disposed one each side of a predetermined fixed direction which bisects that angle, two polar diagrams which overlap are obtained, said predetermined direction being termed the axis of the system and being characterised (if the diagrams are identical) by equal field strengths. The axial direction is thus easily determined by reason of this equality of strength but any other direction off the axis can only be determined by making absolute measurements of field strengths obtained on the two diagrams, a complex and difficult matter and one prone to considerable error in view of the liability to erratic atmospheric field strength variations. Measurement of absolute values can be avoided and any direction can be determined by arranging for mechanical movement of the aerial system to bring its equi-field strength axis into the direction to be determined, but this expedient has the obvious difficulties, defects and disadvantages inherent in mechanical movement, more especially the difficulties of training an aerial accurately over small, accurately measured angles and changing direction rapidly.

The present invention has for its object to avoid the difficulties and defects above referred to, and to provide improved and simple radio directional systems whereby directions may be determined rapidly and with precision without requiring any mechanical movement of the aerial system used and without involving absolute measurements of field strengths and whereby the momentarily determined direction may be swept, rapidly if desired, through an arc.

According to this invention, two overlapping polar diagrams are produced and the relative amplitudes of these

2

are varied in accordance with a predetermined periodic law to vary the direction of the axis of the system.

The periodic law of amplitude variation may be a saw tooth law, but other laws are possible for example triangular.

A system according to the invention may comprise a directional aerial with two associated wave guides providing two overlapping secant polar diagrams having their maxima at a small angle to one another, the required amplitude variation being obtained by electrically controlled means for oppositely modifying in alternation the transmission coefficients of the guides. Instead of using two guides and a common aerial there may be two separate guides and aerials.

15 The electrically controlled means associated with each guide may be a magnetron, the fields of which are such, that it cannot oscillate, said magnetron being coupled to its guide so as to impart therein a variable impedance dependent on the anode cathode voltage of the magnetron, control being effected by varying this voltage.

20 Control may be effected by producing two square waves which are applied one to each of the two magnetrons, these waves having impulses and intervals of equal durations and having their pulse amplitudes varied in opposite senses, said waves being applied to control said magnetrons so that when one cuts off its associated guide the other opens its guide introducing therein a transmission coefficient proportional to the impulse amplitude and vice versa.

25 30 For transmission the two guides may be fed from the same source of energy of very high frequency.

For reception the two guides may feed a comparison receiver adapted to determine the moments of input signal amplitude quality from the two guides.

35 The invention is illustrated in and further explained in connection with the accompanying drawings in which:

Figure 1 is a graphical figure illustrating the polar diagrams of a known equi-field strength system, the abscissae representing angles and the ordinates the field strengths.

Figure 2 is a similar graphical representation illustrating the operation of this invention.

Figure 3 is a block diagram showing principal parts of a system according to the invention.

40 Figure 4 shows diagrammatically a transmitter system embodying the invention.

Figure 5 shows an electronic modulator which may be used in the system of Figure 4.

Figure 6 is a curve connecting the transmission coefficient in the region 30 of the guide 3 of Figure 5 with voltage V applied at point a_1 to the magnetron in Figure 5.

55 Figures 7 and 8 represent graphically voltage waves for application at a_1 and a_2 respectively of Figure 4 in order to sweep the axis of field strength equality through the desired angle.

Figure 9 represents in greater detail the generator 7 of Figure 4 which provides the voltages of Figures 7 and 8.

60 Figures 10 and 11 represent two recurrent voltage wave forms for the generators G_1 and G_2 used in Figure 9 for modulation to obtain sweeping of the axis.

Figure 12 represents diagrammatically apparatus which may be connected to the apparatus of Figure 3 to provide a receiving system.

65 In the well known so-called equi-signal method of determining ultra-high frequency signal direction conventionally illustrated in Figure 1, an aerial has its direction alternated between two values $x(+\alpha_0)$ and $x(-\alpha_0)$ such that there are two overlapping identical polar diagrams L_1 and L_2 alternately produced, overlapping on

the line $OX(o)$ with regard to which they are symmetrical, the two diagrams appearing alternately in a predetermined rhythm or periodic manner. The direction $OX(o)$ is characterised by the existence of the same field strength whichever diagram L_1 or L_2 is present.

In order to ascertain the direction of a signal in some other direction $x(\alpha)$ making an angle α with $OX(o)$, either the whole system must be swung through the angle α to point in the new direction, or the field strengthens E_1 and E_2 due to the diagrams L_1 and L_2 respectively must be measured, the difference $(E_1 - E_2)$ enabling the value of α to be deduced if the forms of the diagrams L_1 and L_2 are known with precision. It is, however, usually not convenient to swing the whole system, and it is difficult to ascertain direction by determining $E_1 - E_2$ with an acceptable degree of accuracy because the absolute values of the fields E_1 and E_2 must be measured.

According to this invention, two polar radiation diagrams which are symmetrical as regards directivity with relation to a predetermined direction are produced and are varied in amplitude in opposite senses in accordance with a predetermined periodic law of variation, so that when the diagram to one side of said predetermined direction is being increased in amplitude, the other is being decreased and vice versa. This is illustrated in Figure 2 from which it will be seen that all the diagrams to the left of $OX(o)$ —the predetermined direction—have directivity $x(-\alpha_0)$ while all those to the right have directivity $x(+\alpha_0)$, the two directives being symmetrical about the axis $O(X)_0$. Six diagrams are shown, three, L_{11} , L_{12} , L_{13} of different amplitudes to the left of the axis and three L_{21} , L_{22} , L_{23} of different amplitudes to the right of the axis. The order of production of these diagrams is L_{11} and L_{21} then L_{12} and L_{22} and then L_{13} and L_{23} . . . and so on, the diagram amplitudes on one side increasing while those on the other decrease and vice versa. When the diagrams L_{11} and L_{21} are produced, the equi-field strength condition will be produced for the direction $x(+\alpha_0)$ at an angle $+\alpha_0$ with the axis. When diagrams L_{12} and L_{22} are produced, the equi-field strength direction is the axial direction and when L_{13} and L_{23} are produced, the equi-field strength direction is the direction $x(+\alpha_0)$. Although for simplicity in drawing, only three diagrams are shown each side of the axis, in practice the number employed is very high—it may be infinite—so that as the amplitude on one side increases and that on the other side decreases and vice versa, the direction of equi-field strength sweeps through an angular sector ($x(-\alpha_m)$ to $x(\alpha_m)$) and back. It is preferable to make use only of the substantially linear regions of the diagrams thereby to avoid possible ambiguities, and generally to increase the precision and the simplicity of the apparatus.

An apparatus for carrying out the invention may comprise as represented diagrammatically in Figure 3, an aerial system 5, 6 constituted by a reflector and two horns (not shown) or by two reflectors each having an associated horn. The aerial 5, 6 is fed from two wave guides 3 and 4 which lead to the two horns, one to each (slots or dipoles may be used instead of horns) which energise the aerial. The arrangement is such that when the feeds to the two horns are equal the aerial has two substantially identical overlapping polar radiation diagrams in directions $OX(\alpha_0)$ $OX(-\alpha_0)$ which are symmetrical with relation to the axis $O(x_0)$. Associated with the guides 3, 4, is a device 1, 2 electrically controlled by control means 7 as represented by the leads b_1 , a_1 , b_2 , a_2 . The device 1, 2 which is controlled, is in essence a variable attenuator arrangement adapted to modify the transmission coefficients of the guides so as to increase that of guide 3 and decrease that of guide 4 (and vice versa) smoothly and similarly. The portions of the guides in advance of the differential attenuation control device 1, 2 are marked 3' and 4' and when the arrangement is used for directional transmission,

these are connected to transmitter apparatus for equal energisation. For directional reception they are, of course, connected to receiver apparatus.

Figure 4 shows another arrangement which is similar in principle. In Figure 4 there are two distinct aerials or horns 5' and 6' fed from the wave guides 3 and 4 respectively. The guide parts 3' and 4' are joined and fed from a conventional ultra-high frequency wave transmitter 8 such as a magnetron transmitter. The wave guides 3, 3' and 4, 4' are rectangular and may be designed for transmission of H_{01} waves. The oppositely acting attenuation control means—the means 1, 2 for modulating the transmission coefficients of the guides in Figure 3—are shown in Figure 4 as constituted by two distinct and separate units 1' and 2', both controlled by the device 7.

Figure 5 shows one suitable form which may be used for attenuation control e. g. for insertion between guide lengths 3' and 3 in Figure 4. In Figure 5, a magnetron 20 M_0 having a cavity anode A connected to earth and an axial cathode K heated by a heating filament (not shown) has the electrical control voltage from device 7 (not shown in Figure 5) applied to its cathode from terminal a_1 . The magnetic field of the magnetron is perpendicular to the plane of the drawing and is produced by a magnet of known type not shown. The magnetic field and the electric voltage applied at a_1 are never such as to permit the magnetron M_0 to oscillate. The magnetron is coupled, for ultra-high frequency, with a branch guide 3a by means of a probe conductor S. The depth of penetration of the probe S into the branch 3a and the position of a piston adjuster P of well-known form provided in the end of the branch 3a are adjusted experimentally by trial and error until the assembly consisting of the branch and its associated equipment produces a desired mean value of transmission coefficient from 3 to 3', or in the opposite direction 3' to 3. As already stated the whole arrangement is such that over the whole range of variation of the control voltage applied at a_1 , the magnetron cannot oscillate, and thus forms a passive impedance with regard to the guide. This impedance is, however, variable as a function of the voltage applied at a_1 . This variation is caused by variations of the space charge around the cathode of the magnetron M_0 under the influence of variations of the electric voltage applied at a_1 , the said variations of space charge modifying the impedance proper of the magnetron with regard to the ultra-high frequency waves which circulate in the guide.

Referring to Figure 6 the arrangement of Figure 5 is experimentally adjusted so that of the voltage applied at a_1 varies from V_m to V_M , the transmission coefficient of the guide 3 to 3' varies between $T'm$ and $T'M$. The values of V_m and V_M are so chosen that operation occurs in the region where the transmission coefficient T' at point 30 (Figure 5) varies substantially linearly with relation to V . $T'm$ is much lower than unity, so that the guide is practically cut off if the voltage applied at a_1 is below V_m while $T'M$ is in the neighbourhood of unity so that with voltage V_M applied the guide is practically without attenuation at 30.

Thus by applying at a_1 and a_2 (from b_1 and b_2) voltages as represented in Figures 7 and 8 respectively, i. e. voltage impulses of duration τ , and of amplitude varying linearly as a function of time in the indicated sense, one of the guides will be blocked ($T'=0$) at any moment whilst the other offers a transmission coefficient T' lying between $T'm$ and $T'M$, and vice versa. T' varies linearly as a function of time in an opposite sense for the two lines. Thus the system of Figure 4 constructed as described with reference to Figure 5 and controlled by voltages as represented in Figures 7 and 8 will produce the changing transmission polar diagrams as described with reference to Figure 2.

The voltages represented in Figures 7 and 8 are sup-

plied by the control device 7 of Figure 4. Figure 9 shows one form for this control device. It comprises a periodic synchronising voltage generator G_s which controls a generator of square waves or pulses G_0 in which the pulses and the intervals between them are of equal duration. This generator G_0 supplies two such pulse trains or square waves which differ only in that the maxima in one wave occur simultaneously with the minima in the other one wave. One wave is applied to the control grid g_1 of one of two conventional triode tubes and the other is applied to the control grid g_2 of the other. These grids are connected to earth through resistances R_{g_1} and R_{g_2} of large values and they also have applied thereto modulating voltages which periodically vary in opposite sense in accordance with saw tooth laws, these voltages being supplied by saw tooth generators G_1 and G_2 synchronised by the synchronising generator G_s . The outputs from the anodes A_1 and A_2 of the two triodes are taken from across resistances R_1 and R_2 through which said anodes are connected to a source of anode voltage at $+HT$. The triodes are operated over the linear parts of their characteristics. Voltages as shown in Figures 7 and 8 are obtained at b_1 and b_2 . It is to be understood that the duration τ of the pulses and the period T of increase and decrease of amplitude of the said pulses are related by the expression

$$\frac{T}{\tau} = n$$

n being other than a whole number.

The modulating voltages V_{G_1} , V_{G_2} supplied by the generators G_1 and G_2 may be, as already stated, saw tooth waves as shown in Figure 10, in which case the equi-field strength axis of the system will sweep across in one direction and return sharply, the transmission or reception circuits (as the case may be) being blocked during flyback. It is, however, possible to modulate by voltages V_{G_1} , V_{G_2} as shown in Figure 11, in which case the axis will sweep back and forth at the same speed. This form of law is herein termed a triangular law.

Of course, modulation may be effected in the triodes of Figure 9 by superimposing voltages from sources G_1 and G_2 on the anodes of the valves or in any other known way.

Figure 12 shows receiving apparatus which may be used in conjunction with the apparatus represented in Figure 3 to provide a receiving system.

Referring to Figure 12 the guide parts 3' and 4' (of Figure 3) feed into detectors D_1 and D_2 whose modulation outputs are fed to a comparison circuit C. The latter controls one pair of deflection plates P_1 and P_1' of a cathode ray tube O_s which are arranged to supply a vertically deflecting signal thereto when the outputs from D_1 and D_2 are equal. The second pair of plates P_2 and P_2' is controlled by a time base generator B_a which is connected to the comparison circuit C through terminals C_1 , C_2 and the lead shown, this connection serving to synchronise the time base by voltages detected at D_1 and D_2 , so that the said time base is synchronised with the period of sweep of the axis. Accordingly the trace of the spot on the screen of the cathode ray tube will exhibit a peak indicating the direction of the incoming signal.

In the arrangement of Figure 4 as described for transmission, the ultra-high frequency energy supplied by the transmitter 8, may be continuous wave energy as has been assumed. It is, however, equally possible to use a pulse generator at 8 i. e. a generator supplying pulses of ultra-high frequency. In this case the pulse generation is preferably synchronised with the unit 7. This is indicated in Figure 4 by a connection $c-d$. The terminal d of unit 7 (Figure 4) then corresponds to the terminal d of the synchronising generator G_s of Figure 9. With this arrangement the impulses from generator 8 will coincide with those of Figures 7 and 8 (and thus with

those of the generator G_0 in Figure 9) and the said impulses from unit 8 will be inside those of Figures 7 and 8.

Again if desired, transmitter 8 may have supplementary signal modulation for synchronising the time base sweep of the cathode ray tube in a co-operating receiver. Where the transmitter is thus modulated, a co-operating receiver may be of known type, or it may be as described herein. Where however an ordinary transmitter is used, the receiver must be as described herein.

We claim:

1. A method of radio direction determination by ultra-high frequency waves which consists in producing alternately two overlapping radiation polar diagrams whose line of intersection defines the direction, and oppositely varying the amplitudes of said diagrams according to a predetermined periodic law having a period substantially greater than the duration of the production of said polar diagrams.

2. A method as claimed in claim 1 wherein the said law is a saw tooth law applied so that the variation of amplitude of one of the said diagrams is in opposite sense to that of the other.

3. An ultra-high frequency directional radio system comprising radio directional means connected with two wave guides and adapted to provide, in co-operation therewith, two secant polar diagrams which overlap, the maximum directions of said diagrams being inclined to one another, and electrically controlled means in each of said guides for modifying alternately the values of the transmission coefficients for electro-magnetic waves in said guides in accordance with two similar but opposite periodic laws of increase and decrease.

4. A system according to claim 3 wherein the said electrically controlled means comprise two magnetrons each having an anode and a cathode, means for applying to said magnetrons magnetic and electro-static fields such that they are always outside the range of self oscillation, means for coupling one of said magnetrons to each of said guides to impart therein a variable impedance dependent on the electric voltage applied between the magnetron anode and cathode, and means for varying said voltage.

5. A system according to claim 3 wherein the said electrically controlled means comprise two magnetrons each having an anode and a cathode, means for applying to said magnetrons magnetic and electro-static fields such that they are always outside the range of self oscillation, means for coupling one of said magnetrons to each of said guides to impart therein a variable impedance dependent on the electric voltage applied between the magnetron anode and cathode, means for producing two recurrent electric voltages having the form of impulses of equal duration, means for varying the amplitudes of said voltages in opposite senses and means for applying the amplitude varied recurrent voltages to the magnetrons so that when one of the magnetrons cuts off the associated guide the other one opens its associated guide introducing therein a transmission coefficient proportional to the amplitude of the impulse applied thereto and vice versa.

6. A system according to claim 3 wherein the said electrically controlled means comprise two magnetrons each having an anode and a cathode, means for applying to said magnetrons magnetic and electro-static fields such that they are always outside the range of self oscillation, means for coupling one of said magnetrons to each of said guides to impart therein a variable impedance dependent on the electric voltage applied between the magnetron anode and cathode, means for producing two recurrent electric voltages having the form of impulses of equal duration, means for varying the amplitudes of said voltages in opposite senses, means for applying the amplitude varied recurrent voltages to the magnetrons so that when one of the magnetrons cuts off the associated guide the other one opens its associated guide introducing

therein a transmission coefficient proportional to the amplitude of the impulse applied thereto and vice versa, and a common ultra high frequency transmitter coupled to both guides.

7. A system according to claim 3 wherein the said electrically controlled means comprise two magnetrons each having an anode and a cathode, means for applying to said magnetrons magnetic and electro-static fields such that they are always outside the range of self-oscillation, means for coupling one of said magnetrons to each of said guides to impart therein a variable impedance dependent on the electric voltage applied between the magnetron anode and cathode, means for producing two recurrent electric voltages having the form of impulses of equal duration, means for varying the amplitudes of said voltages in opposite senses, means for applying the amplitude varied recurrent voltages to the magnetrons so that when one of the magnetrons cuts off the associated guide the other one opens its associated guide introducing therein a transmission coefficient proportional to the amplitude of the impulse applied thereto and vice versa, and a common signal comparing receiver adapted to determine and indicate the moments of equality of amplitude of the signals fed thereto from said guides.

8. A method of determining the angular position of a first point with respect to a second point and to an axis passing through said second point comprising the steps of: emitting ultra-high frequency energy from one of said points, alternately concentrating said energy at said second point into two lobe patterns intersecting each other while continuously switching said energy from one

lobe to the other, oppositely varying the amplitude of said lobe patterns according to a predetermined periodic law, the intersection of said lobe patterns determining a direction which is along said axis when the amplitude is equal for each of said lobe patterns, receiving said ultra-high frequency energy at the other of said points, and determining the instant of equality between the energy respectively received from both said lobes whereby the absolute angular position of said first point with respect to said axis is determined.

9. In the method of determining the angular position of a first point with respect to a second point and to an axis passing through said second point of the type comprising the steps of radiating ultra-high frequency energy from one of said points, receiving said energy at the other of said points, concentrating said energy at either of said points into two lobe patterns intersecting along said axis, and continuously switching said energy from one lobe to the other: the step of oppositely varying the amplitude of said energy in said lobes, the period of the variation of said amplitude being substantially greater than the period of switching said lobes.
